UNITED STATES PATENT OFFICE.

PAUL E. FENTON, OF THOMASTON, CONNECTICUT, ASSIGNOR TO SCOVILL MANUFACTURING COMPANY, OF WATERBURY, CONNECTICUT, A CORPORATION OF CONNECTICUT.

SELF-LOCKING PIN FASTENER.

Application filed April 19, 1928. Serial No. 271,346.

The invention will be explained in connection with its use for fastening covers to the upholstered parts, such as the seats, of automobiles, but it is to be understood that 5 it is not intended thereby to limit its use.

The invention consists of a double-pointed or multi-legged pin, having its legs shouldered in relation to its upper or head portion, and the remainder of its legs spaced 10 apart, so that when the legs are stuck into an article and pushed toward their head a relatively large area of the article will be gathered in between the legs and forced past the shouldered parts and thereafter allowed to expand to some extent above the 15 shouldered parts, so that the fastener is more or less firmly locked in set position and so rendered secure against accidental displacement, as I will proceed now to explain 20 more fully and finally claim.

In the accompanying drawings illustrating the invention, in the several figures of which like parts are similarly designated, Figure 1 is a front elevation; Fig. 2 is a rear 25 elevation, and Fig. 3 is a longitudinal section illustrating a capped embodiment of the invention, the shouldered parts of the pin being more or less inclined. Fig. 4 is a rear elevation of the pin shown in Figs. 1-3, detached. Fig. 5 is a rear elevation 30 of a modified form of pin, detached, in which the shouldered parts are at substantially ninety degrees to the vertical portions of the head of the pin.

Describing the invention as illustrated in the drawings, the pin is composed of a length of wire doubled upon itself in spaced-apart relation, and formed with the reverted head 1. The legs 2, 2 have the upper 35 portions 3, 3 parallel with one another and overlying the head 1 and parallel with its sides, and these portions 3, 3 are drawn in at an angle to the upper portions, as at 4, 4, so as to cause the limbs to converge and 40 form shoulders. Below the shoulders 4, 4, the legs are spread apart or diverge, whereby their points 5, 5 enter the material to be pinned at distant points, so that when the 45 pin is pushed home the material will be 50 gathered in or bunched as the shoulders are

neared, and after such points are passed the material will spread out in the parallel space above the shoulders, and thus the pin will be more or less securely locked on or in the article to be secured. The purposed 55 withdrawal of the pin from the article is resisted by the shoulders but may be accomplished by exerting sufficient force.

As shown in Figs. 1 to 4 the shoulders are inclined to facilitate withdrawal, but in 60 Fig. 5 the shoulders 4' are arranged substantially at ninety degrees to the head and thereby greater resistance to withdrawal is afforded.

I have shown the pin of this invention 65 provided with a cap 6, applied to the head of the pin by engagement with the flange 7. To further ensure the engagement of the cap with the pin, there are employed 70 a lug 8 on the cap bent down between the 70 legs of the pin next to the head and a tongue 9 which projects from the flange of the cap between the sides of the head and is bent down over the looped portion 10 of the head. 75

As already sufficiently indicated, the legs of the pin are stuck into the article to be fastened, and as the pin is pushed home, the material will be gathered or bunched between the legs as they converge upwardly 80 toward the shoulders and then forced through said shoulders 4 so as to pass into the space above these parts, where the material is free to relax or expand. Thus it will be seen that the shoulders serve the 85 purpose of locking the pin in the material in a more or less secure manner. When the shoulders are made on an incline, as shown in Figs. 2 and 4, the withdrawal of the pin from the material is retarded or obstructed 90 by friction, whereas in the case of the pin shown in Fig. 5, there is a positive locking action.

The broad invention includes not only the diverging legs where the divergence is continuous from the shoulders 4 to the points of the legs, but also any arrangement where the upper parts of the legs are shouldered and the legs extend thence downwardly and are spaced apart sufficiently to gather in or 100

bunch the material to which the pin is applied and crowd it past the shouldered portions.

Near the points of the pin legs, the wire of the pin has the greatest resilience, and this resilience decreases as the upper part or head of the pin is approached. When the pin is being set or mounted, the material on which the pin is set has the benefit of more resiliency through the lateral movement of the legs than when the pin is withdrawn, because the shoulders are nearer the top of the legs.

Variations in the details of construction are permissible within the principle of the invention and the scope of the claims following.

What I claim is:—

1. A self-locking pin fastener, having a head and a plurality of legs, the legs being shouldered in relation to the head and the remainder of the legs spaced apart, whereby when the legs are stuck into an article and pushed toward their head a relatively large area of the article will be gathered in between the legs and forced past the shouldered parts and thereafter allowed to expand above the shouldered parts, so that the fastener is firmly locked in set position and rendered secure against accidental displacement.

2. A self-locking pin fastener, comprising a pin, having a plurality of legs and a head bent back upon and overlying said legs, said legs adjacent to said head being provided with shoulders forming an obstruction and said legs extending below the shoulders in spaced-apart relation.

3. A self-locking pin fastener, comprising a pin having a plurality of legs and a fixed head bent back upon and overlying said legs, the legs of the pin adjacent to the head being drawn in toward one another to form an obstruction and the legs of the pin extending beyond the obstruction.

4. A self-locking pin fastener, comprising a pin having a plurality of legs and a head bent back upon said legs, the legs of the pin adjacent to the head being drawn in toward one another to form an obstruction and the legs of the pin extending beyond the obstruction and spaced apart from one another below the obstruction.

5. A self-locking pin fastener, comprising a pin having a plurality of legs and a head bent back upon said legs, the legs of the pin adjacent to the head being drawn in toward one another to form an obstruction, the legs of the pin toward their points being spaced apart a distance greater than the extent of the obstruction, whereby in the use of the pin its points will enter the material of the article on which it is used at points relatively widely separated and as the pin is pushed in toward its head the material will be gathered in or bunched between the legs and

forced past the obstruction and allowed to expand between the legs above such obstruction to overcome any tendency toward accidental escape of the fastener.

6. A self-locking pin fastener, comprising a pin having a plurality of legs and a head bent back upon and overlying said legs, the legs of the pin adjacent to the head being shouldered to form an obstruction and said legs extending beyond these shoulders and diverging therefrom.

7. A self-locking pin fastener, comprising a pin having legs and a head bent back upon said legs, the legs of the pin adjacent to the head being bent toward one another to form shoulders and the legs of the pin extending beyond these shoulders and diverging therefrom, the diverging legs serving to enter the material to be fastened over a relatively wide area and gather in or bunch the material between them, and such gathered-in material being crowded between and past the adjacent points of the shoulders.

8. A self-locking pin fastener, comprising a pin having a pair of legs and a head bent back upon said legs and forming parallel sides, the adjacent portions of the legs of the pin also being parallel one to the other and to the sides of the head, and drawn-in parts resiliently closing the space above between the legs.

9. A self-locking pin fastener, comprising a pin having a plurality of legs and a head bent back upon said legs and forming parallel sides, the adjacent portions of the legs of the pin also being parallel one to the other and to the sides of the head, and drawn-in parts resiliently closing the space above between the legs, the remainder of the legs below the drawn-in parts diverging.

10. A self-locking pin fastener, comprising a two-legged pin having a head bent back upon and overlying said legs, the legs of the pin adjacent to the head being drawn in toward one another at substantially right angles to the head of the pin to form an obstruction and the legs of the pin extending beyond these drawn-in parts.

11. A self-locking pin fastener, comprising a pin having a plurality of legs, a head bent back upon the legs of the pin, the legs of the pin adjacent to the head being shouldered to form an obstruction which is adapted to prevent the accidental escape of the fastener and the legs of the pin extending beyond these shouldered parts, and a cap secured to and covering-in the head of the pin.

In testimony whereof I have hereunto set my hand this 18th day of April, A. D. 1928.

PAUL E. FENTON. 125
